TURBINE

Christopher A. Schellens, Marblehead, Mass., assignor to C-S Engineering Company, Englewood, N. J., a corporation of Delaware

Application March 26, 1932, Serial No. 601,375

10 Claims.

(Cl. 253—71)

This invention relates to steam turbines especially adapted, although not necessarily restricted, to driving centrifugal water pumps for supplying locomotive boilers with feed water.

5 The turbine with which this invention is particularly concerned is of the Curtis type having one or more nozzles which convert the pressure of the steam into velocity and a turbine wheel having two velocity stages from one to the other 10 of which the steam is passed in succession. The invention is also applicable to other types of turbines having a turbine wheel provided with two or more successive pressure stages.

The usual two-stage turbine wheel has two 15 axially-spaced rows of buckets from one to the other of which rows the steam is guided in succession. A turbine driven locomotive feed water pump is subject to high over speeds at times when the pump accidentally becomes dry and the over-speed tripping mechanism fails to operate, as may 20 happen when the mechanism is not inspected at reasonable intervals. When over-speeding occurs the connections between the turbine buckets and the wheel are subjected to severe stresses sufficient, sometimes, to cause the buckets to leave 25 the wheel. Hence an object of the present invention is the provision of a turbine construction which permits the buckets to be welded in a commercial manner to the wheel so that they are in 30 effect integrally connected so strongly therewith as to resist high centrifugal forces.

A turbine wheel having two rows of buckets can not have its buckets welded readily to the wheel since the bucket rows are so close together 35 that welding can not be done at any commercial speed between the rows. Hence a further object of the invention is the provision of a two-stage turbine having but one row of buckets on its wheel, so that the single row of buckets can be 40 welded readily to the wheel while preserving the advantages of the two reaction passages.

It is a further object of the invention to provide a turbine wheel with a single row of buckets which are so arranged as to provide outer and 45 inner sets of moving reaction passages, or stages, through which the steam passes from one side to the other of the wheel together with a stationary passage on one side of the wheel for directing the steam into one set of reaction passages and a 50 stationary reversing passage on the other side of the wheel which receives the steam from said set of reaction passages and redirects the steam toward the first side of the wheel and into said other set of reaction passages. Said passages, 55 or one or more of them, may or may not provide

for the expansion of the steam therein, at the will of the designer.

It is also an object of the present invention to direct the steam to enter the sets of reaction passages in such order that the difference in 5 peripheral speeds of the sets of passages is most nearly in accord with the velocities of the steam entering the passages and, for this purpose, with the specific construction in which the invention is herein illustrated, to enter the upper portion of 10 the bucket first and the lower portion last.

The direction of flow of the steam passing through the one portion of the buckets must be reversed to be directed into the other portion of 15 the buckets and a further object of the invention is the provision of a novel form of reversing chamber adapted for this purpose.

A further object of the invention is generally to improve the construction and operation of steam turbines.

Fig. 1 is a sectional elevation of a steam turbine embodying the present invention.

Fig. 2 is a developed section taken along line 2—2 of Fig. 1.

Fig. 3 is a sectional side elevation of the buckets 25 of the turbine wheel.

Fig. 4 is a front elevation of one of the reversing chambers.

Fig. 5 is a section along line 5—5 of Fig. 4.

Fig. 6 is a section taken along line 6—6 of 30 Fig. 4.

As here shown, the turbine embodying the present invention comprises a casing 10 having a steam chest 12 into which steam is admitted through the pipe 14. The steam chest is in communication with a block 16 having a row of passages 18 therein which direct the steam into the wheel buckets. As herein shown, the passages 18 constitute expanding nozzles each comprising the bowl 20 and the expanding passage 22. A valve 23 is provided which is adapted to be closed by over-speed mechanism, not shown, when the turbine speed becomes excessively high and shut off the supply of steam to the nozzles. The nozzles discharge steam through the turbine buckets hereinafter to be described and finally into the wheel chamber 24 of the casing from which the exhaust steam is discharged through the outlet 26. The wheel chamber is closed by the removable cover 28. A turbine wheel 30 is located in 50 the wheel chamber and comprises a radial disc 32 having a central hub 34 that is fixed to the drive shaft 36. The drive shaft is suitably supported in bearings 38, one of which is here shown, and connected to the centrifugal pump or other 55

power consuming device not herein shown. The wheel disc is provided with an enlarged rim 40 in which an endless peripheral bucket groove 42 is formed, the side walls of the groove being parallel. The peripheral faces 44 of the rim on the opposite sides of the groove are inclined inwardly toward the shaft for a purpose to be explained hereinafter. The turbine wheel is provided with a series of buckets 46 which nest one within the other and have shanks or roots 48 that are located in the bucket groove 42 and are welded to the wheel. The opposite faces of the roots of the buckets are provided with grooves 50 which are located about flush with the top faces of the wheel rim on opposite sides of the groove. The material of the wheel rim is peened into the grooves 50 whereby to hold the buckets firmly in position during the welding operation. The buckets are then welded to the rim by applying welding material 52 to the inclined faces 44 of the rim and to the buckets on both sides of the bucket, as illustrated in Fig. 1, thereby building up the rim on both sides of the buckets and forming an effective bond between the buckets and the rim so that the buckets and rim are in effect one integral mass. The body of the buckets, above the roots, are formed with upwardly and outwardly inclined bottom faces 53 which oppose the rim faces 44 and cooperate therewith to form V-shaped channels in which the welding material can be deposited to form a strong bond between the wheel and buckets.

Each bucket is provided with a shroud plate 56 at the top and a second shroud plate 58 in the middle thereof, each shroud plate extending behind the bucket and nesting against the front face of the next adjacent bucket so that the buckets are provided with isolated outer and inner steam reaction passages 60 and 62, respectively, the inner passages being radially longer than the outer passages. The opposite sides of the middle shroud plates 58 are provided with peripheral grooves 64 for the purpose of lightening the buckets. The upper shroud plates 56 form in effect an endless shroud which is machined off to provide an apex 65 in the median line or at the outermost diameter of the wheel. The wheel is balanced by removing the material where necessary from the apex 65, where the least material has the most effect on the balance of the wheel. The wheel is located in its chamber with the buckets adjacent the nozzles 18 so that the steam discharged from the nozzles must pass through the outer steam passages 60 of the buckets, thereby to rotate the wheel. The steam leaving the outer passages of the buckets is directed through a series of reversing chambers 66 which confront the nozzles on the opposite sides of the wheel and by them is directed into the inner steam passages 62 of the buckets.

The reversing chambers are identical. Each comprises a block 68 the outer end of which is located in an arcuate groove 70 of the cover plate 28 of the wheel chamber and has a flat end face 72 that is seated in the bottom of said groove. The block is provided with a stud bolt 74 which projects through the cover plate and has a nut screw-threaded thereon whereby to hold the block removably in position. Each block is provided with arcuate side walls 78 and 80 curved in the direction of rotation of the wheel, and so arranged that the blocks seat one against the other, whereby the open reversing chamber 66 of one block is closed by the next adjacent block. The open reversing chamber for the first block of the series

is covered by a cover member 82 which is separately secured to the turbine casing in the same manner as the blocks 68. The reversing chamber 66 of each block comprises relatively straight upper and lower passages 84 and 86 which are separated by a wall 88 and are connected at the rear by an arcuate connecting passage 90, the cross-sectional area of the passages preferably increasing progressively from the inlet of the upper passage to the exit of the lower passage to compensate for loss in steam speed in the passage due to friction therein. The entrance to the chamber is at a somewhat different angle than the discharge from the chamber so that the steam is taken from the outer portion of the buckets and is delivered to the inner portion without shock, the angle of the lip 92 of the wall 78 for the upper passage being greater than that of the lip 94 of the lower passage, the material of the wall 78 being filed away, or otherwise removed, at the lip 92, as indicated by the dotted lines, Fig. 5, for this purpose.

With the construction above described one row of buckets and the reversing chambers take the place of the usual two rows of buckets, thereby reducing the cost of the turbine and also permitting the buckets to be welded economically to the wheel, so that they can resist successfully the high centrifugal stresses to which they may be subjected if the wheel overspeeds.

The weight of the wheel is also lighter than that of the usual two-row type, which is important, especially in high speed turbines. With the type of turbine illustrated, there is no harmful axial thrust on the wheel since the steam pressures on opposite sides of the wheel are the same, there being no particular expansion of steam in the buckets. The efficiency of the turbine as thus constructed has been found to be about the same as with the usual two-velocity stage construction.

With the particular type of turbine herein chosen to illustrate the invention, the main expansion of the steam from the high to the exhaust pressure occurs in the nozzles 18, the steam passing through the bucket passages and the reversing chambers 66 with little or no drop in pressure. The proportion of the reversing chambers may obviously be such as to permit of a drop in pressure therein. Or the bucket passages can be made to expand the steam as it passes therethrough, as in the Parsons type of turbine in which case the nozzles 18 and the reversing chambers may not have expanding passages. The application of the invention is the same regardless of where the steam is expanded.

I claim:

1. A turbine comprising a turbine wheel having a row of buckets provided with outer and inner passages therebetween, a nozzle which directs steam into one of said passages, and a series of steam reversing members which receive the steam from said passage and reverse the direction of flow thereof and direct it into said other passage, said reversing members being arranged in contiguous relation and each having a reversing chamber therein that is open on one side only, which side is closed by the contiguous reversing member.

2. A turbine as defined in claim 1, there being a cover member free from a reversing chamber and which closes the open reversing chamber of the end reversing member of the series.

3. A turbine comprising a casing having a wheel compartment, a turbine wheel therein having a row of buckets provided with outer and in-

ner steam passages therebetween, nozzles which direct steam into one of said passages, said casting having a wall confronting said wheel opposite said nozzles and provided with an arcuate groove 5 therein, a series of separate identical reversing blocks located in said groove in contiguous relation, each block having a generally U-shaped passage therein provided with an inlet opposite the exit of one bucket passage and an exit opposite the inlet of the other bucket passage, the passage 10 between its inlet and exit being open on the side facing the wheel, and the contiguous block overlying said open passage and constituting the closure therefor, and a passage-free cover plate 15 overlying the open passage of the end block of the series.

4. In a turbine having a bucket wheel, a nozzle for directing steam through the buckets, and a series of separate identical but nested reversing 20 blocks each having therein a reversing passage having a reverse bend in the middle, an inlet confronting the bucket exits and an exit confronting the bucket inlets and arranged to receive steam from the buckets and to redirect the steam to re-pass through the buckets.

5. In a turbine having a bucket wheel, a nozzle for directing steam through the buckets, and a series of separate identical but nested reversing 25 blocks each having a reversing passage having a reverse bend in the middle, an inlet confronting the bucket exits and an exit confronting the bucket inlets and arranged to receive steam from the buckets and to redirect the steam to re-pass through the buckets, said passages being curved 30 in a direction axially of the wheel, whereby to increase the dimensions of said passages transverse to the wheel as they approach said reverse bends.

6. In a turbine having a bucket wheel, a nozzle 40 for directing steam through the buckets, and a series of separate identical but nested reversing blocks each having a reversing passage having a reverse bend in the middle, an inlet confronting the bucket exits and an exit confronting the 45 bucket inlets and arranged to receive steam from the buckets and to redirect the steam to re-pass through the buckets, the dimension of each passage transverse to the wheel increasing as the passage approaches the bend.

50 7. In a turbine having a bucket wheel, a nozzle for directing steam through the buckets, and a series of separate identical but nested reversing blocks each having a reversing passage having a

reverse bend in the middle, an inlet confronting the bucket exits and an exit confronting the bucket inlets and arranged to receive steam from the buckets and to redirect the steam to re-pass through the buckets, the dimension of each passage transverse to the wheel increasing as the passage approaches the bend and the dimension of each passage radially of the wheel decreasing as the passage approaches the bend.

8. In a turbine having a bucket wheel, a nozzle 10 for directing steam through the buckets, and a series of separate identical but nested reversing blocks each having therein a reversing passage having a reverse bend in the middle, an inlet confronting the bucket exits and an exit confronting 15 the bucket inlets and arranged to receive steam from the buckets and to redirect the steam to re-pass through the buckets, the nested faces of said blocks being arcuate and cylindrical and the reversing passages being open in the cylindrical 20 faces of said blocks.

9. In a turbine having a bucket wheel, a nozzle for directing steam through the buckets, and a series of separate identical but nested reversing 25 blocks each having therein a reversing passage having a reverse bend in the middle, an inlet confronting the bucket exits and an exit confronting the bucket inlets and arranged to receive steam from the buckets and to redirect the steam to re-pass through the buckets, the nested faces 30 of said blocks being arcuate and cylindrical, one side of each passage being open in a cylindrical nesting face thereof and one block constituting a cover for the open side of the passage in the adjacent block.

10. In a turbine having a bucket wheel, a nozzle for directing steam through the buckets, and a series of separate identical but nested reversing 40 blocks each having a reversing passage having a reverse bend in the middle, an inlet confronting the bucket exits and an exit confronting the bucket inlets and arranged to receive steam from the buckets and to redirect the steam to re-pass through the buckets, the nested faces of said blocks being arcuate and cylindrical, one side of 45 each passage being open in a nesting face thereof, and one block constituting a cover for the open side of the passage in the adjacent block, the end portion of the bottom wall of the block opposite the open face of the passage being inclined with 50 respect to the median line of the passage.

CHRISTOPHER A. SCHELLENS.
